Specification for Design.

Patented Mar. 9, 1920.

Application filed October 25, 1919. Serial No. 333,404. Term of patent 14 years.

To all whom it may concern:

Be it known that I, HERMAS PELLAND, a subject of the King of Great Britain, and resident of Davisville Hospital, in the city of Toronto, county of York, Province of Ontario, in the Dominion of Canada, have invented a new, original, and ornamental Design for a Motor-Driven Vehicle, of which the following is a specification, reference being had to the accompanying drawings, forming part thereof.

In the drawings Figure 1 is a side elevation of the motor driven vehicle.

Fig. 2 is a plan view of the vehicle from above.

Fig. 3 is a front elevation of the vehicle.

What I claim is:

The ornamental design for a motor driven vehicle as shown.

Signed at the city of Toronto, this eighth day of October, 1919.

HERMAS PELLAND.
